Primary Examiner — Robert M Spear*Assistant Examiner* — Kendra L Hamilton(74) *Attorney, Agent, or Firm* — Foley & Lardner LLP(51) **LOC (10) Cl.** **24-04****CLAIM**(52) **U.S. Cl.**

We claim the ornamental design for a fluid dispensing pacifier, as shown and described.

USPC ..... **D24/194****DESCRIPTION**(58) **Field of Classification Search**

FIG. 1 is a top, front, and left side perspective view of a fluid dispensing pacifier;

USPC D30/160; D1/106, 125, 199; 119/707, 119/709; 606/234, 235, 236; D24/193, 194, D24/195, 196, 214, 117, 199; D21/625, D21/627, 659

FIG. 2 is a bottom, rear, and right side perspective view thereof;

CPC A61J 17/00; A61J 17/02

FIG. 3 is a front view thereof;

See application file for complete search history.

FIG. 4 is a rear view thereof;

(56) **References Cited**

FIG. 5 is a right side view thereof;

U.S. PATENT DOCUMENTS

FIG. 6 is a left side view thereof;

3,353,714 A	11/1967	Trecek
3,862,684 A	1/1975	Schmitt
3,993,223 A	11/1976	Brady et al.
